(57) **CLAIM**

The ornamental design for an applicator, as shown and described.

DESCRIPTION

FIG. 1 is a top perspective view in closed condition of the design;

FIG. 2 is a side view in closed condition view thereof;

FIG. 3 is an opposite side view in closed condition view thereof;

FIG. 4 is a bottom perspective view in closed condition view thereof;

FIG. 5 is a side view of the applicator shown with the lid removed;

FIG. 6 is another side view thereof;

FIG. 7 is an exploded view from the top view thereof;

FIG. 8 is an exploded view from the bottom view thereof; and,

FIG. 9 is an exploded side view thereof.

The broken lines shown in the figures depict portions of the applicator that form no part of the claimed design.

1 Claim, 6 Drawing Sheets
